(57) **CLAIM**

The ornamental design for a sprinkler head accessory, as shown and described.

DESCRIPTION

FIG. 1 is a front elevational view of a sprinkler head accessory showing my new design;

FIG. 2 is a rear elevational thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view thereof;

FIG. 8 is a cross-sectional view thereof, taken in the direction of line 8-8 of FIG. 1;

FIG. 9 is a front elevational view of the sprinkler head accessory and an outer cover of a sprinkler head, wherein the sprinkler head accessory is in a using position with the outer cover; and,

FIG. 10 is a cross-sectional view thereof, taken in the direction of line 10-10 of FIG. 9.

In FIGS. 1-10, the broken lines which illustrate the center area feature of the article depict portions of the sprinkler head accessory that form no part of the claimed design.

The broken lines shown around the sprinkler head accessory in FIGS. 9 and 10 depict the environment of an outer cover that forms no part of the claimed design.

1 Claim, 10 Drawing Sheets
